UNITED STATES PATENT OFFICE.

WLADYSLAW MAKOWIECKI, OF PHILADELPHIA, PENNSYLVANIA.

BOMB THROWER.

Application filed March 2, 1923. Serial No. 622,322.

To all whom it may concern:

Be it known that I, WLADYSLAW MAKOWIECKI, a citizen of Poland, residing at Philadelphia, county of Philadelphia, and 5 State of Pennsylvania, have invented certain new and useful Improvements in Bomb Throwers, of which the following is a specification.

This invention relates to improvements in 10 bomb throwers, and it is the principal object of my invention to provide a device of this kind in form of a gun in which a grenade or shell adapted to be ejected from the gun by a spring controlled ejector mechanism, will impart to the bomb the necessary velocity as it is ejected from the gun.

In combination with the device having the above characteristics, the invention aims as a further object to provide a novel construction, combination and arrangement of 15 parts.

In the accompanying drawings forming a material part of this invention:

Figure 1 is a top plan view of my improved bomb thrower constructed according to the present invention.

Figure 2 is a side view thereof.

Figure 3 is a transverse section through the bomb thrower, along line 3—3 of Figure 1.

Figure 4 is a detail side elevation of a wheel.

Figure 5 is a top plan view upon the rear end of the bomb thrower, partly in section.

Figure 6 is a sectional side elevation of the ejector mechanism, the section being taken on line 6—6 of Figure 5.

Figure 7 is a detail view of a trigger 40 mechanism.

Figure 8 is a longitudinal section through the gun barrel.

Figure 9 is an end view of the grenade or shell carriage, and

Figure 10 is a side view thereof.

The bomb thrower comprises in the main a gun barrel 10 mounted on a carriage 11 resting on wheels 12. The barrel 10 is held in place upon the carriage 11 between vertical standards 13 securely fastened with their foot parts 14 to the carriage and carrying at their upper, bent ends two clamping members 15 and 16 respectively, facing each other and firmly clamped around the outer 55 mantle of the gun, and provided with clamp-

ing ears 17, firmly held in place by means of bolts 18 and nuts 19 on top and below the gun barrel 10.

The ejector mechanism is arranged at the rear end of the gun and is encased in a housing 20 closed at its rear end by a lid 21 hingedly connected to the housing 20 as at 22 and within the housing 20, an ejector slide 23 is provided carrying the grenade or shell 24. This slide is provided with grooves 25 in its side walls near the bottom thereof with which it is guided within the casing or housing 20, the inner side walls of which are provided with suitable slats engaging the grooves 25.

To the bottom of the slide 23 a strap 38 is fastened, the end of which is guided over a drum 29 and a second drum 30 below the first drum on the shaft of which a pinion 31 is arranged in mesh with a gear 32 and a crank shaft 33 journaled between the upper ends of standards 34 by means of which arrangement the ejector slide 23 can be drawn to the rear end of the housing 20 against the action of a number of springs. 80 One of these springs 35, is arranged between a cross-head 36, sliding within a chamber 37 in the gun barrel, and the inner end face of the ejector slide 23 to which the cross-head is secured by means of straps 85 26 and 27.

Laterally disposed to the ejector slide in the housing 20 to both sides of the barrel are springs 40 and 41, sliding in housing 20 in which cross-heads 28 are disposed, to 90 which one end of a strap 28' is secured, the other end of which is fastened to the bottom of slide 23, a groove 42 within the bottom of the ejector carriage 23 is adapted to be engaged by the point 43 of a trigger 95 rod 44 when the carriage is in its extreme rearward position. Between the point 43 and the rod 44 the standard 45 for the rod 44 is provided with a chamber 46 within which a spring 47 is wound around the rod 44 between the point 43 and the bottom of the chamber 46.

To the lower end of the rod 44 a cable 48 is attached, a pull on which relieves the trigger point 43 from its engagement in 105 groove 42 of the ejector slide so that the same under the action of the springs will be moved forward to eject the shell 24 into the barrel. At the mouth of the barrel a suitable seat 49 for a bomb 50 is provided 110

which has a detonator at its point and a seat or anvil 51 at its rear end against which the shell 24 strikes to throw the bomb.

It will be clear that changes may be made in the general arrangement of my device and the specific construction of its details without deviating from the scope or spirit of my invention.

What I claim as new and desire to secure 10 by Letters Patent of the United States is—

1. A bomb thrower of the character described comprising a barrel having a seat for the bomb, an ejector slide at its opposite end, adapted to fire a shell to eject the bomb, 15 means for normally holding said ejector slide in its rear position of rest, means for releasing said slide to fire the shell, and means for guiding said slide back into its rear position ready for firing after each firing operation.

2. A bomb thrower of the character described, comprising a barrel having a seat at its mouth for a bomb, a casing, an ejector slide within said casing, straps at the bottom 25 of said slide, springs tending to impart to said slide a motion towards the mouth of the gun, means for winding said straps upon drums against the action of said springs, means for holding said slide in its retracted 30 position, and means for releasing said holding means to fire the shell against a bomb on said seat for throwing said bomb.

3. A bomb thrower of the character described comprising a barrel, a seat at the 35 front end of said barrel for a bomb, a housing at the opposite end of said barrel, an ejector slide slidably mounted within said housing, provided with a groove at its bottom, straps secured to said slide, a plurality 40 of drums for said straps, means for winding said straps upon said drums, a plurality of springs normally tending to move said slide forward, a means engaging the groove in the bottom of said slide to hold 45 the same in retracted position against the

action of said springs, and means for releasing said holding means to move said slide forward and to project a shell on said slide against a bomb on said seat for ejecting the same.

4. A bomb thrower of the character described comprising a barrel, a seat near the mouth of said barrel for a bomb to be thrown, a housing at the opposite end of said barrel, guides in said housing, an ejector slide adapted to carry a shell sliding along said guides and having a groove in its bottom, a plurality of springs normally tending to move said slide forward to project the shell, straps, secured to the bottom 55 of said slide, a plurality of drums, a crank shaft for rotating said drums to wind the cables on said drums, a spring controlled trigger pin adapted to engage the groove in the bottom of said slide for holding the slide 60 in its retracted position, a cable attached to the outer end of said pin for disengaging it from said groove to allow a projection of said slide by said springs for projecting the shell from said slide through the barrel 65 against the bomb on said seat for throwing the same.

5. In a bomb thrower of the character described, a barrel, a seat for a bomb on said barrel, an ejector slide at the opposite end 70 of said barrel, a cross-head sliding in said barrel, an ejector slide, bars securing said cross-head to said slide, a strong spring between said cross-head and said slide, a plurality 75 of springs laterally disposed to said slide, normally tending to move the same forward, means for holding said slide in its retracted position, against the action of said spring and means for releasing said slide to project a shell therein against a bomb on 80 said seat for throwing the same.

In testimony whereof I have affixed my signature,

WLADYSLAW MAKOWIECKI.
